DESIGN FOR A COSMETIC CONTAINER

Marguerite H. Ramsey, Brooklyn, N. Y.

Application January 15, 1946, Serial No. 125,572

Term of patent 3½ years

(Cl. D86—10)

To all whom it may concern:

Be it known that I, Marguerite H. Ramsey, a citizen of the United States, residing in Brooklyn, county of Kings, State of New York, have invented a new, original, and ornamental Design for Cosmetic Container, of which the following is a specification, reference being had to the accompanying drawing, forming a part thereof, in which:

Fig. 1 is a front elevational view of a cosmetic container, showing my new design in closed position;

Fig. 2 is a side elevational view of the container with the cover removed therefrom;
Fig. 3 is a top plan view with the cover removed;
Fig. 4 is a bottom plan view of the design; and
Fig. 5 is a top plan view of the design with the cover in place.

I claim:

The ornamental design for a cosmetic container, as shown and described.
